UNITED STATES PATENT OFFICE.

ELMER A. WILCOX, OF LOS ANGELES, CALIFORNIA.

AUTOMOBILE-JACK.

1,276,469.

Specification of Letters Patent. Patented Aug. 20, 1918.

Application filed October 3, 1917. Serial No. 194,569.

To all whom it may concern:

Be it known that I, ELMER A. WILCOX, a citizen of the United States, residing at Los Angeles, in the county of Los Angeles and State of California, have invented new and useful Improvements in Automobile-Jacks, of which the following is a specification.

This invention relates to an automobile jack.

10 When using an automobile jack to raise the axles of motor vehicles, the point to which the jack is to be applied is very often inconveniently situated and thus necessitates that a person must crawl under the machine 15 to properly set the jack. It is the principal object of this invention to provide a jack which is so constructed as to allow it to be easily positioned at any desired remote point and operated without inconvenience.

20 Another object of this invention is to provide a jack which will accomplish the above purpose and which will hold itself rigidly at the end of the operating handle while being positioned beneath the car, thus allowing 25 it to be accurately set.

Another object of this invention is to provide means whereby the operating mechanism of the jack may be unlocked after the jack has been placed at a remote point and 30 will insure that the lifting bar of the jack will be released to become properly adjusted beneath the object to be raised without manipulation of the lifting mechanism, and which will also insure that the jack will be 35 held rigidly against tipping so that the handle may be easily moved to actuate the operating mechanisms.

It is a further object of this invention to 40 provide a jack of the above construction and for accomplishing the above named results which is simple in its construction and operation and may be locked in a compact manner when not in use.

Other objects will appear hereinafter.

45 The invention is illustrated, by way of example, in the accompanying drawings in which:

Figure 1 is a view in side elevation illustrating the jack as having parts broken 50 away to more easily disclose the operative mechanism within the housing of the jack.

Fig. 2 is a view in elevation illustrating the side of the jack upon which the handle is mounted and disclosing the normal closed 55 position of the jack in solid lines, as well as

an extended position of the lifting bar in dotted lines.

Fig. 3 is a fragmentary view in side elevation illustrating the housing of the jack and particularly disclosing the manner in 60 which the pawl release pin is made accessible.

Fig. 4 is a view of the telescoping handle used upon the jack, said view disclosing the handle as in its extended position.

Fig. 5 is a fragmentary view of the foot and lower portion of the jack housing illustrating in detail the manner in which the lifting bar of the jack is locked against upward movement.

Fig. 6 is a view in transverse section on the line 6—6 of Fig. 5 and illustrates the two compartments which extend lengthwise of the jack housing to receive the lifting bar and the expansion spring.

Referring more particularly to the drawings, 10 indicates the outer case or housing of the jack. This housing is preferably formed of cast metal and has an enlarged flat foot 11 upon which the jack stands. The 80 housing is formed with two vertically extending compartments, a lifting bar compartment 12, which is rectangular in section, and an expansion spring compartment 13, which is circular in section. These compartments extend parallel to each other and substantially the length of the housing. A longitudinally extending pin slot is formed through the partition wall between the two compartments and substantially the length 85 thereof. The opposite wall of the bar compartment is formed with a rectangular opening 15 which is surrounded upon three sides by a pawl housing 16 cast integral with the housing 10 and extending outwardly therefrom. This pawl housing has parallel side walls formed as continuations of the side walls of the main housing, and an inclined end wall 17. This wall does not entirely cover the opening 15 in the side of the bar 90 compartment and thus forms an inclined passage-way 18 through which a portion of the operating mechanism of the jack is mounted.

A socket pivot pin 19 extends across the 105 opening 18 and through the side walls of the pawl housing 16. This pivot pin is provided as a support for a handle socket 20 through an extension 21 of which it passes. The handle socket is thus disposed directly be- 110

low the opening 18 in the pawl housing and normally stands at an inclination to the vertical and so that it may have a desired range of movement upon its pivot 19. The socket proper is formed with a central cylindrical opening which extends the length thereof to receive one end of a handle 22. This handle is formed with a shoulder 23 which is brought to bear against the upper obliquely disposed face of the socket and limits the movement of the handle therethrough. As particularly shown in Fig. 4, the handle is designed to telescope, being formed of separate sections reduced in diameter and which may be telescoped one within the other. The use of this extensible handle permits the jack to be easily placed at a desired point beneath the car without requiring that the operator reach the point at which the jack is to rest.

The handle socket and its handle are provided to actuate lifting pawls 24 and 25 by which a lifting bar 26 is raised. These pawls are pivotally secured to the socket extension 21 by a pair of pivot pins 27 which are disposed upon opposite sides of the socket pivot 19 and in alignment therewith, said pins being arranged on a line substantially parallel to the center of the handle and its socket. The pawls are superimposed one above the other. The lowermost pawl 24 is short and is adapted to be held against the side of the lifting bar 26 by a leaf spring 28 which is fastened to the under side of the upper pawl 25. The upper pawl is held against the same side of the lifting bar and at a point above the lower pawl by a leaf spring 29 secured to the upper side of the pawl 25 and bearing at its outer end against the inclined wall 17 of the pawl housing. These two pawls are adapted to normally register with serrations 30 formed along the side of the lifting bar. These serrations have square horizontal faces and outwardly inclined connecting faces over which the ends of the pawls may move to abut against the square faces and carry the weight of the lifting bar. The upper end of the lifting bar is formed with a head 31 which provides an enlarged surface adapted to support the object to be lifted. The two pawls may be simultaneously moved from the supporting position beneath the square faces of the serrations by a release pin 32 which is fixed to the side of the lower pawl 24 and extends through an opening 33 in the side of the housing. Movement of this pawl by the pin in the direction of the arrow —a— will cause the pawl to bear against spring 28 and in turn swing the pawl 25 in the direction of the arrow —b— and clear of the side of the lifting bar, thus allowing the bar to be lowered within its compartment.

A means is provided for instantly adjusting the lifting bar beneath the object to be

raised, said means being actuated by the handle 22 and from a remote point. This means comprises an expansion spring 34 positioned within the expansion spring compartment 13. This spring, when expanded, extends substantially the length of its compartment within which it is retained by an inserted collar 35 which is fastened within the top of the compartment. A spring block 36 is provided to seat within the upper end of the spring 34 and has an enlarged flange which holds it in position over the end of the spring. This block is adapted to bear against a lifting bar pin 37 which extends outwardly from the side of the lifting bar opposite the serrated side and mid-way the length thereof. However, when the lifting pawls 24 and 25 elevate the lifting bar and its pin 37 above the maximum expansive length of the spring, the pin will pass upwardly and away from the block 36 and through the collar 35 at the top of the spring compartment 13. The spring 34 is provided to permit the lifting bar to be self-adjusting beneath the object to be raised. Thus, under normal conditions and when the jack is not in use, the lifting bar is held downwardly in the position shown by solid lines in Fig. 2 and against the expansive action of the spring 34. This is accomplished by a locking lever 38 mounted at the side of the housing upon a pin 39 and at a point below the pawl housing 16. This lever has a lower arm 40 upon which an inturned extension finger 41 is formed. The finger 41 is adapted to register with a groove 42 formed across the lowermost serration. The lower lip of the groove 42 is cut away to provide clearance for the pawl 24 so that the lifting bar may be lifted to an extreme position. A lever arm 43 forms the upper portion of the locking lever 38 and extends upwardly to a point adjacent the end of the socket 20. At this point it has a curved face which may be engaged by the end of the handle 22 when the handle is forced through the socket to its seated position. A leaf spring 44 normally holds the arm 43 of the lever outwardly and the finger 41 of the arm 40 inwardly.

In operation, it will be first assumed that the jack has been used and that its lifting bar is extended. It may then be closed by movement of the pin 32 in the direction of the arrow —c— as shown in Fig. 3. This will act, as previously described, to simultaneously swing the pawls 24 and 25 outwardly from the side of the lifting bar in the directions indicated upon the two pawls, respectively, by the arrows —a— and —b—. When this has been done, the lifting bar may be forced downwardly against the expansion of the spring 34 until the end of the bar strikes the inturned finger 41 of the locking arm 40. When the bar strikes this finger the pawls are then released and allowed to

swing in against the serrated side of the locking bar. At this time their ends will fall substantially mid-way the distance between the two squared shoulders of certain 5 serrations. The arm 43 of the locking lever 38 is then pressed inwardly to swing the arm 40 of the lever and its finger 41 outwardly to permit the lower lip of groove 42 to pass the finger, after which the lifting 10 bar is further forced in a downwardly direction until the ends of its pawls strike the squared ends of the serrations with which they were in register. The locking lever may then be released and its finger will 15 pass into the groove 42 to prevent upward movement of the lifting bar and at the same time to lock the pawls and the handle socket against movement. Thus, it will be seen that when the jack is folded in its 20 operative position all of the parts will be locked against movement and rattle will thereby be eliminated.

When the jack is to be used, the handle is extended and placed loosely within the 25 socket 20 of the jack. Attention is directed to the fact that the handle is not forced into the socket until the shoulder strikes the upper edge of the socket, but part way therethrough so that the end of the handle will 30 not forcefully strike the upper end of the locking lever 38. It is also to be borne in mind that the entire jack mechanism is locked rigid so that the handle and jack may be manipulated as a single member. The 35 handle is then grasped and the jack placed beneath the car at a desired remote point, the length of the handle permitting this to be conveniently accomplished. After the jack has been properly located, the handle 40 may be forced into the socket to cause its lower end to forcefully bear against the curved end face of the arm 43 of the locking lever 38. This will cause the finger 41 of the locking lever to swing outwardly from engagement with the groove 42 at the bottom 45 of the lifting bar and thereby release the lifting bar so that the spring 34 may instantly lift the bar and cause it to become adjustably held against the under face of 50 the object to be lifted. It will then be noted that the pawls are free to move and as the handle 22 is oscillated upwardly and downwardly the pawls will successively act to lift the bar. As the pawls are designed in 55 the present instance, one of them will raise the lifting bar the length of half of one of the serrations while the other pawl is lowering to engage a serration and raise the bar the other half of a serration length. Thus 60 the pawls will coöperate to lift the bar and rigidly hold it beneath the object lifted. When the object is to be lowered, the automobile is shoved forwardly or pulled by the engine and will thus ride off of the jack and 65 onto ground. The jack may then be folded

up as previously described and will be ready for another operation.

It will thus be seen that the jack here shown is comparatively simple in its construction, may be easily placed, held in place, and operated at remote points beneath an automobile, and will act in a self-adjusting manner to position itself beneath the object to be raised after which the object may be easily raised.

While I have shown the preferred construction of my automobile jack as now known to me, it will be understood that various changes in the combination, construction and arrangement of parts may be made by those skilled in the art without departing from the spirit of my invention as claimed.

I claim:

1. An automobile jack comprising a housing, a lifting bar, operating means for elevating the lifting bar, a handle whereby the jack may be positioned and operated from a remote point, a spring member adapted to raise the lifting bar independent of its operating means and to dispose the head of the 90 bar against the face of the object to be lifted, a trip-member adapted to control and release said spring member, and means whereby the handle of the jack may actuate the trip member.

2. An automobile jack comprising a housing, a lifting bar, an operating mechanism for elevating said lifting bar, a socket formed as a part of said mechanism, a handle adapted to be positioned within said socket, spring means for elevating the lifting bar independent of said operating means, and means whereby movement of the handle through its socket will cause said spring means to be released to elevate said bar.

3. An automobile jack comprising a housing, a lifting bar, an operating mechanism for elevating said lifting bar, a socket formed as a part of said mechanism, a handle adapted to be positioned within said socket, spring means for elevating the lifting bar independent of said operating means, a trip catch lever disposed adjacent the lower end of said socket and provided to normally render the spring means inoperative, and means whereby the handle will actuate said trip means to release the spring means when the handle projects through the socket and engages the trip-lever.

4. An automobile jack comprising a housing, a vertically movable lifting bar positioned therein, operating means for elevating said bar inclosed within the housing, a handle socket provided and connected to said operating means, a handle adapted to be positioned within said socket when the jack is to be operated, a spring by which the bar may be instantly lifted, a trip-lever adapted to normally prevent operation of said spring and which may be released by the movement 130

of the handle as it passes through the end of the socket, and means whereby the operating mechanism, the lifting bar, the handle socket, and the spring may be held rigidly 5 when the trip lever is set.

5. An automobile jack comprising a housing, a vertically movable lifting bar inclosed therein, a pair of pawls adapted to alternately engage the lifting bar, a handle which 10 may be oscillated to produce said alternate operation of the pawls and raise the lifting bar, and spring means released by the handle whereby the lifting bar may be automatically disposed beneath the object to be lifted 15 in position to be immediately raised.

6. An automobile jack comprising a housing having an enlarged base portion by which it is supported and having a pair of openings extending vertically substantially 20 the length thereof, a lifting bar slidably mounted within one of said openings, a helical spring positioned in the other opening, a pin upon the lifting bar adapted to normally rest upon the upper end of the spring, 25 a series of serrations formed along the opposite side of the lifting bar from the pin, a handle sleeve pivotally mounted upon the housing, a pair of pawls pivotally secured to the handle sleeve and adapted to register

with the serrations upon the lifting bar, a 30 removable handle adapted to be positioned within the sleeve and by which the sleeve may be oscillated to alternately cause the pawls to lift the bar the length of one serration, means for normally locking the lifting 35 bar in its lowermost position, and means whereby the movement to insert the handle within the handle sleeve will act to release the lifting bar and cause it to be elevated to bring its head to bear against the under face 40 of the object to be lifted.

7. An automobile jack comprising a base, a lifting bar supported in the base, a handle, pawl and ratchet for operating the lifting bar, a spring for compressing the lifting bar 45 against the load, means for locking the handle and holding the spring compressed and the lifting bar withdrawn; so that by manipulating the handle the jack may be placed in position for operation; and means operated by the handle for releasing the handle and releasing the lifting bar; so that the spring will press the lifting bar against the load and hold the jack in position while the handle is manipulated to lift the load. 50

In testimony whereof I have signed my name to this specification.

ELMER A. WILCOX.
